(57) **CLAIM**

The ornamental design for a blood pressure measuring apparatus, as shown and described.

DESCRIPTION

FIG. 1 is a front perspective view of a blood pressure measuring apparatus;

FIG. 2 is a front view thereof;

FIG. 3 is a right side view thereof;

FIG. 4 is a top plan view thereof;

FIG. 5 is a rear view thereof;

FIG. 6 is a left side view thereof;

FIG. 7 is a bottom plan view thereof;

FIG. 8 is a sectional view taken along line 8-8 of FIG. 2; and, FIG. 9 is a reference perspective view thereof showing a state in which this article is used.

The broken lines in FIG. 9 represent environmental subject matter. The broken lines showing the inner element in FIG. 6 and the internal components in FIG. 8 are included for the purpose of illustrating portions of the blood pressure measuring apparatus that form no part of the claimed design. None of the broken lines form a part of the claimed design.
